Primary Examiner — Lakiya Rogers*Assistant Examiner* — Harold E Blackwell, II(74) *Attorney, Agent, or Firm* — Dennis J. Williamson; Moore & Van Allen PLLC(57) **CLAIM**

We claim the ornamental design for a LED lamp, as shown and described.

DESCRIPTION

FIG. 1 is a front view showing an embodiment of our new design for a LED lamp;

FIG. 2 is a right side view showing our new design shown in FIG. 1;

FIG. 3 is a back view showing our new design shown in FIG. 1;

FIG. 4 is a left side view showing our new design shown in FIG. 1;

FIG. 5 is a bottom view showing our new design shown in FIG. 1; and,

FIG. 6 is a top view showing our new design shown in FIG. 1.

The broken lines in the drawings illustrate portions of a LED lamp which form no part of the claimed design.
